UNITED STATES PATENT OFFICE.

CHARLES T. TOULMIN, OF NEW YORK, N. Y.

BOILER.

SPECIFICATION forming part of Letters Patent No. 554,383, dated February 11, 1896.

Application filed June 18, 1895. Serial No. 553,243. (No model.)

To all whom it may concern:

Be it known that I, CHARLES TUCK TOULMIN, a citizen of the United States, and a resident of the city, county, and State of New York, have invented a new and useful Improvement in Boilers; and I do hereby declare that the following is a full, clear, and exact description of the same.

This invention relates in particular to low-pressure sectional boilers for heating purposes of the kind described in Letters Patent No. 521,995, issued to me June 29, 1894; and among its objects are to increase and improve the water-heating surface, to improve the means for regulating the draft, to provide for repairing the grate without extinguishing the fire, and to otherwise simplify and improve the construction.

In order that my invention may be clearly ascertained I shall first describe in detail the mode in which I carry the invention into practice, and then point out the various features in the claims.

Reference is to be had to the accompanying drawings, forming part of this specification, in which like parts are designated by the same letters in all the figures.

Figure 1 is a front elevation of a boiler embodying my present invention. Fig. 2 is a side elevation of the same. Fig. 3 is a cross-sectional elevation of the same on the line 3 3, Fig. 4. Fig. 4 is a longitudinal sectional view of the same on the line 4 4, Fig. 3. Fig. 5 is a front elevation of one of the sections of the boiler. Fig. 6 is a sectional side view on the line 6 6, Fig. 3. Fig. 7 is a perspective view of a part hereinafter referred to.

I construct the body of my boiler of a variable number of transverse vertical hollow interior sections A, a vertical water-back section B and a vertical hollow front section C, all of which sections abut, substantially as described in my aforesaid prior patent, No. 521,995, and may be bound together by tie-bolts or by the supply and return pipes, as shown.

Each interior section A is cast with side water-legs A' A², a transverse water-head A³, and dome A⁴, a water-waist A⁵ and a water-bridge A⁶ of less thickness than the water-legs, the combined spaces below the water-waists A⁵

forming the combustion-chamber, and the vertical spaces between the water-bridges forming a succession of vertical flues communicating with the combustion-chamber, substantially as described in my aforesaid prior patent, No. 521,995. In the form of boiler here shown, however, I form draft-openings both above and below the water-bridges A⁶ of all the sections A and arrange dampers D in said draft-openings alternately above and below the water-bridges A, so that by closing all of said dampers the zigzag flue referred to in my said prior patent is formed, while by opening said dampers a more or less direct draft is obtained as may be desired.

In my present invention I form the water-bridges A⁶ of all the sections at one side thereof and form the sections with water-pillars E at the inner ends of the water-bridges, the combined spaces between the abutting water-pillars E, the water-legs A', the water-waists A⁵, and the water-heads A³ forming a longitudinal return-flue F, which leads from the vertical flues between the water-bridges A⁶ at the front of the boiler to the draft-opening G in the back section B, so that the products of combustion may be led through the zigzag flue between the water-bridges A⁶ to the front of the boiler and then by the return-flue F to the back of the boiler, thereby greatly increasing the effective heating-surface of the boiler. I likewise form the water-back section B with a draft-opening H, leading outward from the back of the combustion-chamber, and provide said draft-opening H with a damper H' and also the return-draft opening G with a damper G'. These direct and return draft openings H and G, I connect by means of a draft-box J, attached to the back section B, with the escape-flue K, so that the products of combustion may be led directly to the escape-flue K by opening the damper H', to strengthen the draft, or by closing said damper H' may be led through the vertical and return flues to the escape-flue, the draft then being regulated by the damper G'.

I generally prefer to corrugate the part of the water-back section B, forming the back of the combustion-chamber, to increase the heating-surface thereof.

In the bottom of the draft-box J, I arrange

an upwardly-opening damper L, by which arrangement I find I am enabled to obtain greatly-improved control of the draft, the cold air being drawn into the box from below.

5 I provide for operating the respective rows of dampers D simultaneously by means of arms D' and connecting-rods D² on the exterior of the boiler, as best shown in Fig. 2.

The supply-pipe M and the return-pipes N, 10 I in this case connect with the dome and water-legs of each section by means of straight coupling-pipes O, having reversely-threaded ends, instead of the bent coupling-pipes shown in my said prior patent.

15 I have also now devised a novel form of grate, consisting of an independent grate-section P for each section of the boiler, which section is introduced through an admission-opening Q in the side water-leg A', and its 20 end gudgeons mounted to turn in sockets R R', the socket R being formed on the inside of the water-leg A² and the socket R' being formed on a removable plate or cover R, (shown in detail in Fig. 8,) which is fastened 25 over the opening Q and can be detached to allow the admission or removal of the grate-section. By this construction I am enabled to remove and repair or replace any section of the grate at will without taking the boiler 30 apart and without extinguishing the fire.

I provide for working the several grate-sections P simultaneously, and thus dumping or controlling the grate by means of detachable rocking arms S, connected by a rod T, and 35 worked by a handle-lever N at the front of the boiler.

The front section C of the boiler is fitted with the furnace-door V, the ash-pit door W, and the door V' for admission to and cleaning both the vertical and return flues.

40 I claim as my invention—

1. A boiler constructed of a number of vertical sections, each formed with side water-legs, a transverse steam and water head A³, 45 a transverse water-waist A⁵, a transverse water-bridge A⁶ of less thickness than the water legs and head, and a water-pillar E at one side of the water-bridge, the combined spaces between the water-pillars and the water-legs

50 forming a longitudinal return-flue connected with the vertical flues between the water-bridges and with the combustion-chamber below the water-waists, and supply and return pipes connected with the head and water-leg of each section, substantially as shown 55 and described.

2. A boiler constructed of a number of vertical interior sections, each formed with side water-legs, a transverse water-waist A⁵, and a transverse water-bridge A⁶ of less thickness 60 than the water legs and head, and a water-pillar E; a vertical rear section provided with a water-back, a damper H' connected with the vertical flues between the water-bridges, and a water-pillar E; a draft-box J, connected 65 both with the damper H' and with the return-flue between the pillars and the water-legs; and supply and return pipes connected with the head and water-leg of each section, substantially as shown and described. 70

3. A boiler provided with a series of openings extending from the fire-box outward through the side of the boiler, a sectional grate, the sections of which are introduced and removable independently endwise through 75 said openings, a series of independently removable covers for the respective openings and independent bearings for the grate-sections at the respective covers and on the opposite side of the boiler, whereby any grate-section may be removed without disturbing the other grate-sections, their bearings or the fire, as set forth.

4. A boiler formed of vertical sections, each of which is provided with a separate opening 85 extending through one water-leg to admit a grate-section from the outside into the fire-box, a separate removable cover for said opening, having a bearing for one end of the grate-section, and a bearing on the opposite water-leg for the other end of the grate-section. 90

In testimony whereof I have hereunto set my hand the 30th day of April, 1895.

CHARLES T. TOULMIN.

In presence of—

HENRY A. RUBINO,
CLARENCE L. BURGER.
